UNITED STATES PATENT OFFICE

JOHN A. WAGNER, OF DECATUR, ILLINOIS

MARKER UNIT

Application filed September 23, 1930, Serial No. 483,911. Renewed September 7, 1932.

This invention relates to a marker unit designed primarily for marking off courses for pedestrians at street intersections and cross-ways, but it is to be understood that a marker unit in accordance with this invention may be employed in any connection for which it may be found applicable, and the invention has for its object to provide, in a manner as hereinafter set forth, a marker unit including a combined marker and anchoring element and a spreader element, and with said elements coacting and constructed in a manner relative to each other to provide for the secure anchorage of the marker unit when the latter is arranged in marking position.

A further object of the invention is to provide, in a manner as hereinafter set forth a marker unit including a combined marker and anchoring element and a spreader element constructed of rust resisting material and having a tendency to remain bright without the foregoing characteristics being given to such elements by a coating or covering of any nature.

A further object of the invention is to provide, in a manner as hereinafter set forth, a marker unit including a combined marker and anchoring element having a one-piece non-coated or non-covered head initially set up with a bright outer surface and as such surface scars or wears away, the same brightness and other characteristics thereof remain as there is no plating or covering to wear completely away. Under such conditions the head, on continued use down to the last 1/16 of an inch thereof will give the same effect as the effect given on the installation of the aforesaid element.

A further object of the invention is to provide, in a manner as hereinafter set forth, a marker unit including a combined marker and anchoring element having a one-piece, non-coated or non-covered head possessing the characteristics to provide a hard wearing surface that will stand considerable abuse, automatically polish itself under continued use as it is worn away and further overcome the disadvantages possessed by a Monel metal head covering as such covering

wears away exposing a dark head, is crimped to the head when positioned on the latter, and wears at its edges resulting in the covering becoming separated from the head.

Further objects of the invention are to provide, in a manner as hereinafter set forth, a marker unit for the purpose referred to and which is simple in its construction and arrangement, strong, durable, compact, thoroughly efficient in its use, readily installed and anchored in marking position, quickly assembled and comparatively inexpensive to manufacture.

With the foregoing and other objects in view, the invention consists of the novel construction, combination and arrangement of parts as hereinafter more specifically described and illustrated in the accompanying drawing wherein is shown an embodiment of the invention, but it is to be understood that changes, variations and modifications can be resorted to which fall within the scope of the claims hereunto appended.

In the drawing wherein like reference characters denote corresponding parts throughout the several views:

Figure 1 is an elevation of a marker unit in accordance with this invention, the elements of the unit being assembled and the unit being in a non-anchored position.

Figure 2 is a view similar to Figure 1 with the unit in an anchored position.

Figure 3 is a section on line 3—3 Figure 1.

Figure 4 is a section on line 4—4 Figure 2.

Figure 5 is an inverted perspective view of a marker unit in accordance with this invention and with the elements of the unit assembled and in a non-anchored position.

Figure 6 is a perspective view of the spreader element.

Figure 7 is a section on a line 7—7 Figure 1.

Figure 8 is a section on a line 8—8 Figure 6.

The unit includes a combined marker and anchoring element referred to generally at 1 and a spreader element referred to generally at 2.

The elements are formed from such metals or alloys of metals to provide a unit which does not require plating or a covering to render it rust resisting and to give it, during

continued use brightness sufficient to make it readily applicable for the usage for which the unit is designed.

The element 1 includes a circular head 2' of segmental cross section. The head 2' has a curved outer face 3. The inner face of the head 2' is formed with a central, circular flat portion 4, an annular flat portion 5 aligning with the portion 4 and an annular groove 6 of arcuate cross section separating the flat portions 4, 5. Although the head is illustrated as of circular form, yet such contour is shown by way of example, as the head can be of any desirable contour other than that shown.

The element 1 further includes a stem formed of three spaced arms 7, 8 and 9 which are integral at their outer ends with the portion 4 of the inner face of the head. Each 20 arm has its outer end disposed at an angle with respect to the portion 4. The integral outer ends of the arms are angularly disposed with respect to each other and in a manner whereby the stem in cross section will be of 25 triangular contour. Each arm is of oblong form. The inner end of each arm is free and indicated at 9. The end 9 is squared. The side edges of each arm are oppositely beveled. The arms are spaced equal distance from 30 each other. The length of the arms is greater than the diameter of the head. The arms provide anchoring members for the element 1 when the unit is set in marking position. The major part of the outer ends of the 35 arms is spaced inwardly from the edge of portion 4. The head and arms are formed of like material. The arms are of the desired thickness. The arms when in anchored position have the inner portions thereof 40 flared outwardly with respect to each other and with respect to the axis of the head of element 1.

The spreader element 2 in cross section is of sexagonal contour. The length of element 45 2 is slightly less than the length of the anchoring members provided by the arms 6, 7 and 8. The element 2 includes a base 10 and an upstanding tapered spreader member 11. The base includes the sides 12, 13, 14, 15, 50 16 and 17. The sides 12, 14 and 16 are of less width than the sides 13, 15 and 17. The upper face of base 10 is downwardly beveled towards the sides 12, 13, 14, 15, 16 and 17 as at 18, 19, 20, 21, 22 and 23 respectively. 55 The member 11 at its lower end is integral with the upper face and is inset with respect to the sides of the base 10. The beveled parts 18, 19, 20, 21, 22 and 23 of the base 10 extend from the lower end of the member 11 to the 60 sides of base 10 and the parts 19, 21 and 23 constitute deflecting surfaces for the arms 6, 7 and 8. The parts 18, 20, and 22 are of less width than parts 19, 21 and 23.

The member 11 is formed with sides 24, 25, 65 26, 27, 28 and 29 and such sides incline in-

wardly from their lower to their upper ends. Each side of member 11 gradually decreases in width from its lower to its upper end. The sides 24, 26 and 28 of member 11 are of less width than the sides 25, 27 and 29. The 70 sides 24, 25, 26, 27, 28 and 29 of member 11, at their lower ends merge into the beveled parts 18, 19, 20, 21, 22 and 23 respectively. The sides 25, 27 and 29 constitute spreading surfaces for the arms 6, 7 and 8. 75

The arms 6, 7 and 8 of the stem are disposed at acute angles with respect to each other. This provides a passage 30 for member 10 of element 2. The openings 31 between the side edges of the arms 6, 7 and 8 are 120 80 degrees apart.

It will be assumed, by way of example, that the unit is to be anchored in a $\frac{7}{8}$ " hole in the concrete. The stem of the combined marker and anchoring element would measure $\frac{7}{8}$ 85 of an inch at three points and this would be sufficient to anchor the marker in a hole or socket of the dimensions referred to. The base of the spreader element would be of slightly less dimensions than that of the stem. 90 The spreader element is mounted in the hole or socket, after which the stem of element 1 is mounted on elements 2, as the element 1 is forced inwardly, the arms 6, 7 and 8 will spread relative to member 11 due to the action 95 of sides 25, 27 and 29. When the squared ends of the arms reach the beveled parts 19, 21 and 23 of base 10 the ends of the arms will be deflected and the arms can pass base 10 until the upper end of member 11 abuts portion 4 of the head 2'. This action crowds the arms 6, 7 and 8 in the wall of the hole or socket at three points and securely anchors the unit in marking position. The element 1 is forced inwardly until the head bears 100 against the surface in which the hole or socket is formed.

It is thought that the many advantages of a marker unit, in accordance with this invention can be readily understood, and although 110 the preferred embodiment of the invention is as illustrated and described, it is to be understood however, that changes in the details of construction can be had which fall within the scope of the invention as claimed. 115

What I claim is:—

1. In a marker unit, a spreader element for a combined marker and anchoring element, said spreader element including a base and a tapered spreader member integral with and 120 inset with respect to the upper face of the base, said member having spreading surfaces and said base having deflecting surfaces, the said surfaces acting on the combined marker and anchoring element to spread the latter to 125 anchoring position.

2. In a marker unit, a spreader element for a combined marker and anchoring element, said spreader element including a base and a tapered spreader member integral with and 130

inset with respect to the upper face of the base, said member having spreading surfaces and said base having deflecting surfaces, the said surfaces acting on the combined marker and anchoring element to spread the latter to anchoring position, said spreading surfaces being spaced from each other, and said deflecting surfaces being spaced from each other.

10 3. In a marker unit, a combined marker and anchoring element including a head and a stem integral at its outer end with the inner face of the head, said stem being of triangular cross section and formed of three arms 15 extending from the inner face of the head and arranged in side edge opposed spaced relation, disposed at acute angles with respect to each other and capable of being shifted to anchoring position on the application of 20 pressure to the inner faces thereof, said head formed throughout of a material possessing the characteristic to offer a bright appearance from continued use.

4. In a marker unit, a combined marker 25 and anchoring element including a head and a stem integral at its outer end with the inner face of the head, said stem being hollow, of triangular cross section and split from its outer to its inner end at spaced 30 points, the material freed by the slits providing arms disposed at acute angles to each other and capable of being spread on the application of pressure to the inner faces thereof to provide anchoring members for 35 said element.

5. In a marker unit, a pair of elements, one of said elements including a marker head and a hollow stem of triangular cross section split, at spaced points from end to end 40 to provide a series of anchoring members, the other of said elements including a base formed with deflecting surfaces and a tapered spreading member formed with spreading surfaces, the said surfaces acting on the 45 inner faces and inner ends of said members for spreading them to anchoring position.

6. In a marker unit, a pair of elements, one of said elements including a marker head and a hollow stem of triangular cross section split, at spaced points from end to end 50 to provide a series of anchoring members, the other of said elements including a base formed with deflecting surfaces, and a tapered spreading member formed with 55 spreading surfaces, the said surfaces acting on the inner faces and inner ends of said members for spreading them to anchoring position, the said spreading surfaces being spaced from each other, and the said deflecting surfaces being spaced from each other.

7. In a marker unit, a pair of elements, one of said elements including a marker head and a hollow stem of triangular cross section 60 split, at spaced points from end to end to

provide a series of anchoring members, the other of said elements including a base formed with deflecting surfaces, and a tapered spreading member formed with spreading surfaces, the said surfaces acting 70 on the inner faces and inner ends of said members for spreading them to anchoring position, said stem being integral at its outer end with the inner face of said head centrally of the latter, and the inner end edge 75 of said stem being squared.

In testimony whereof, I affix my signature hereto.

JOHN A. WAGNER.
